Specification for Design.

Patented June 4, 1918.

Application filed February 27, 1918. Serial No. 219,521. Term of patent 14 years.

To all whom it may concern:

Be it known that I, PAUL RUDERT, a citizen of the United States, and resident of Tarentum, in the county of Allegheny and State of Pennsylvania, have invented a certain new, original, and ornamental Design for a Sound-Box, of which the following is a specification, reference being had to the accompanying drawing, forming part thereof, in which—

Fig. 2 is a bottom plan view of the same.

I claim:—

The ornamental design for a sound box as shown.

In testimony whereof, I, the said PAUL RUDERT have hereunto set my hand.

PAUL RUDERT.
